(57) **CLAIM**

The ornamental design of a ribbed container, as shown and described.

DESCRIPTION

FIG. 1 is a front perspective view of a ribbed container showing the claimed design;

FIG. 2 is a rear elevation view thereof;

FIG. 3 is a front elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a planar cross-sectional view taken along line 8-8 of FIG. 5; and,

FIG. 9 is a planar cross-sectional view taken along line 9-9 of FIG. 4.

The broken lines are for illustrative purposes only and form no part of the claimed design.
